UNITED STATES PATENT OFFICE.

JOHN H. ILLIG, OF BUFFALO, NEW YORK.

WRENCH.

Application filed August 9, 1921. Serial No. 490,876.

To all whom it may concern:

Be it known that JOHN H. ILLIG, a citizen of the United States, residing at Buffalo, in the county of Erie and State of New York, 5 has invented a new and useful Improvement in Wrenches, of which the following is a specification.

This invention relates to wrenches of the kind having fixed and movable jaws and in 10 which the movable jaw may be adjusted toward and from the fixed jaw by means of a nut engaging a threaded stem connected with the movable jaw. In wrenches of this type the threaded stem extends substantially 15 parallel to the base of the movable jaw and in wrenches heretofore devised, the stem was made separately from the movable jaw and secured thereto after it had been threaded. This construction is expensive to manufac- 20 ture and also unsatisfactory owing to the more or less unreliable connection between the movable jaw and the stem.

The objects of this invention are to produce a wrench of this kind by an improved 25 method of manufacture, whereby the movable jaw is provided with an internal threaded stem; also to improve the construction of wrenches in such a manner that the movable jaw of the wrench may be provided with an 30 integral threaded stem; also to improve the construction of wrenches of this kind in the other respects hereinafter specified.

In the accompanying drawings:

Fig. 1 is a face view of a wrench embody- 35 ing the invention.

Fig. 2 is a fragmentary central sectional elevation thereof.

Fig. 3 is a side view of the movable jaw member before the threaded stem has been 40 bent into a position parallel to the base of the movable jaw.

Fig. 4 is an end view of the movable jaw.

Fig. 5 is a section of the wrench on line 5-5, Fig. 2.

Fig. 6 is an end view of a movable jaw of slightly modified construction.

The wrench to which the invention is applied includes as shown in the accompanying drawings, the usual handle A having at 50 one end thereof an enlarged part forming a head B and which is provided with an integral fixed jaw C. The head is provided with the usual longitudinal slot for guiding the movable jaw, the slot shown comprising 55 a neck portion b of reduced width, a guide portion b' connecting with the neck portion

b and preferably formed by drilling a hole lengthwise of the head. The slot also includes a second substantially cylindrical portion b² also formed by drilling a hole 60 lengthwise of the head, the two parallel drilled holes forming the portions b' and b² preferably overlapping or intersecting so that the slots b' and b² are connected. The head of the wrench is also provided with 65 outer flat faces b³ at opposite sides of the slot which terminate at the jaw C. The wrench head also has the usual transverse hole b⁴ extending therethrough and in which an adjusting nut D is arranged. A wrench 70 head of other construction may be used in connection with this invention.

The movable member of the wrench includes a jaw portion E which is adapted to cooperate with the fixed jaw C to grip the 75 work. This jaw portion is connected by means of a neck e of reduced thickness with a base F which is formed to enter into the cylindrical portion b' of the slot, the neck e of the movable member passing through the neck portion b of the slot in the wrench head. As shown, the base F of the movable member is preferably of greater length than the jaw portion E, so as to effectively hold the movable member in position in the head and facilitate easy adjustment of the movable jaw. The jaw portion E is also preferably provided adjacent to the neck e with shoulders e' adapted to engage with the flat faces b³ of the wrench head, so that when 80 the movable member is subject to pressure due to engagement with the work, the jaw will be clamped on the head owing to a binding action of the shoulders e' against the faces b³ of the head and of the base portion F in the cylindrical portion of the slot.

In order to adjust the movable jaw relatively to the fixed jaw, a threaded stem or shank G is provided which in the construction shown is formed integral with the base of the movable member and is connected with the base by means of a flexible reduced neck portion g. This construction makes it 100 possible to form the movable member of the wrench in a single piece and having the stem or shank G extending at an angle to the base F as indicated in Fig. 3. When the stem is arranged in this relation to the base of the movable member, the stem may be 105 threaded by means of the ordinary threading dies. After the threading operation is 110

completed, the stem or shank can be bent into parallel relation with the base of the movable member as shown in Fig. 2, the reduced connecting portion *g*, facilitating the 5 bending of the stem in this manner. When the movable member has been completed, it may be inserted endwise into the slot in the wrench head so that the nut *D* engages the 10 thread of the stem or shank to adjust the movable jaw toward and from the fixed jaw. In the use of the wrench, the portion *g* connecting the stem and the base does not in any way weaken the wrench since the 15 strains to which the movable member is subjected, are not transmitted to the stem *G* but are taken up by the binding action which takes place owing to the fact that the base *F* of the movable member and the shoulders *e'* thereof engage with the cylindrical portion 20 *b'* and the face portions *b'* respectively of the wrench head.

My improved process of manufacturing the movable member of the wrench consists in forming the movable member with a stem 25 *G* extending at an angle to the base *F* and connected thereto at one end of the stem by the connecting portion *g*. The stem or shank is then threaded while in angular relation to the base *F*, the threading being 30 done by the usual thread cutting dies, which could not be used if the stem were originally formed in parallel relation to the base *F*. After the stem has been threaded, it is bent into a position parallel with the base *F*, 35 thus completing the movable member and eliminating the necessity of attaching the stem to the base.

By making the base *F* of the movable member substantially semicircular in cross 40 section, the base occupies only about one half of the drilled hole *b'*. This affords sufficient space for the adjusting nut *D* to enter into the space between the threaded stem *G* and the base *F*, and at the same time makes 45 it possible to drill the two holes *b'* and *b'* so as to intersect. Consequently, by so forming the base *F* that the same occupies only a part of the guide hole *b'*, an inexpensive construction is made possible.

50 Fig. 6 shows a movable member *H* of slightly modified construction, in that this member is made with a stem *h* which extends laterally with reference to the base portion of the jaw. After the stem has been threaded, it is bent to extend substantially 55 parallel to the base portion of the jaw so that the movable member when finished is identical with the one shown in Figs. 1-5.

The wrench described has decided advantages over wrenches heretofore made in that the stem *G* while arranged in angular relation to the base *F* can easily be threaded by

means of the ordinary threading tool which insures an accurate cutting of the thread so that the adjustment of the movable member, 65 by turning the nut *D*, is greatly facilitated. The bending of the threaded stem into correct relation to the base can be very readily effected and requires but a short interval of time. When the stem has been bent into this 70 position, the movable member of the wrench is ready for use and no attaching of the threaded stem to the movable member is necessary. Since the parts of the wrench are usually made of wrought or steel iron, 75 the bending of the stem *G* does not in any way decrease the strength of the metal at the part where the bending takes place.

I claim as my invention:

1. In a wrench, the combination of a head 80 provided with a guide slot and a fixed jaw, said slot including two parallel intersecting holes, a movable jaw having a substantially semi-cylindrical base arranged in one of said intersecting holes, a threaded stem 85 extending substantially parallel to said base in the other of said intersecting holes, and a nut on said threaded stem and extending into the space between said base and said threaded stem.

2. In a wrench having a head provided with a guide slot and a fixed jaw, the combination of a movable member comprising a movable jaw, a base of greater length than said movable jaw, and a neck portion connecting said movable jaw and said base, and a screw threaded stem extending parallel to said base and formed integral therewith and connected to said base by a reduced neck portion, whereby said stem may be bent to 90 and from parallel relation to said base.

3. In a wrench, a movable member comprising a jaw, a base of greater length than said jaw, a neck of reduced thickness connecting said jaw and base, a screw threaded stem integral with and extending parallel to said base, and a reduced neck portion integral with and connecting said base with one end of said screw threaded stem, whereby said stem may be bent to and from parallel relation to said base.

4. In a wrench, a head provided with a guide portion and a fixed jaw, a movable member comprising a jaw, a base connected to said second-named jaw and adapted to move on the guide portion of said head, a stem extending at a side of said base, a flexible connection between said stem and said base, whereby said stem may be screw-threaded and then bent to an operating position with respect to said base, and a nut arranged in said head and adapted to engage said screw-threaded stem.

JOHN H. ILLIG.
